LIGHTING FIXTURE

William D. O'Morrow, La Jolla, Calif.

Application July 12, 1956, Serial No. 597,458

13 Claims. (Cl. 240—10)

The present invention relates to lighting fixtures for gardens and more particularly to the type which is stuck into the earth and which is decorative, employing a translucent shade.

The fixture is carried by a spike and is adjustable vertically and frictionally held in adjusted position.

The shade is preferably formed of a plastic such as a fiber glass-polyester resin or formed of cellulose acetate butyrate sheet material. A member, preferably formed of metal, has a portion or portions thereof embedded in the plastic and has other portions extending outwardly of the plastic, such outwardly extending portions providing a guide for the spike and providing a support and reflector for a lamp.

The reflector lies substantially parallel of the wall of the shade but is spaced therefrom to provide an air space between it and the shade.

Further objects and advantages will be apparent from the following description, reference being had to the accompanying drawing wherein a preferred embodiment of the invention is illustrated.

In the drawings:

Fig. 1 is a front view of the lighting fixture showing the shade and spike in assembled relationship;

Fig. 2 is a rear view of the fixture shown in Fig. 1;

Fig. 3 is a fragmentary sectional view, on a larger scale, the section being taken on line 3—3 of Fig. 2; and

Fig. 4 is a fragmentary sectional view taken along line 4—4 of Fig. 3.

Referring more in detail to the drawing, the fixture includes generally a shade 21 and a spike 22, the spike being used for supporting the shade in the earth. The shade may be formed of any suitable material and is preferably formed of plastic. This plastic, for example, may be fiber glass-polyester resin or formed from a cellulose acetate butyrate sheet. Preferably the shade is translucent and simulates a plant or flower; it is herein shown as simulating three leaves. A member 24, preferably formed of sheet metal, such as sheet aluminum, has two portions 25 and 26 thereof embedded in the wall or shade 21. An intermediate portion 28 extends outwardly from the rear side of the wall 21. This portion 28 includes right angularly extending upper portion 29, right angularly extending lower portion 30, and a connecting portion 31. These right angularly extending portions 29 and 30 are provided with aligned holes 33 and 34 for receiving the upwardly extending shank or rod 35 of the spike. Depressed ears 37 are formed in the interconnecting part 31 to provide retainers for a leaf spring 38. This leaf spring resiliently bears against the shank 35 of the spike 22 for holding the shade in a vertically adjusted position.

The upper end of the embedded portion 24 merges into an outwardly extending portion 40, which is provided with an opening 41 aligned with openings 33 and 34 for receiving the upper end of the shank 35 of the spike 22. The portion 40 merges with a portion 43 which extends upwardly and substantially parallelly with the

2

wall or shade 21. This portion 43 forms a reflector for the rays of light being emitted from the lamp 44.

The lamp 44 is carried by a socket 45 which in turn is carried by a U-shaped spring clip 46. The springs 47 are connected with one another by a yoke 48. A U-shaped slit 49 is formed in the sheet metal adjacent the upper portion 24, to form an ear 50. The yoke 48 is slid under this ear 50, and then the ear is bent towards the main body of the portion 24 to temporarily hold the yoke, and consequently the leaf spring, in position while the portions 24 and 26 and the yoke 28 are being embedded in the plastic. The electric cord for the lamp is shown at 51.

As previously stated, the reflector 43 is arranged parallelly with the shade 21, and it will be seen from Fig. 3 that it is spaced from said shade to provide an air gap 53 for the free circulation of air between the rear of the shade 21 and the confronting side of the reflector 43. This air space 53 in effect insulates the relatively high temperature reflector from the plastic shade. This is important since, if polyester resin is employed, excessive heat tends to discolor the plastic, or, if cellulose acetate butyrate is used, excessive heat deforms the same.

As seen from Fig. 3, the reflector 43 is provided with a light diffusing surface, a simple form thereof being by corrugating the surface. Preferably these corrugations lie in vertically spaced, horizontal planes. It will be observed from Fig. 3 that the reflector is relatively narrow with respect to the width of the shade, and the sides 30 of the shade are curved rearwardly so that some of the light rays strike the same directly. It has been found that, when the reflector 43 is a flat surface, the shadow thereof seen through the translucent shade is too pronounced. By providing the diffused surface on the reflector, the shadow of the shade is more diffused; that is, light rays striking the rear of the shade and rebounding to and from that side of the reflector, which confronts the shade, will cause such diffusion as to minimize the shadow of the reflector.

While the form of embodiment herein shown and described constitutes a preferred form, it is to be understood that other forms may be adopted falling within the scope of the claims that follow.

I claim:

1. In a lighting fixture for a garden, in combination, a translucent wall; a spike adapted to extend into the ground and supporting said wall; a lamp support; and a member having a portion stationarily embedded in said translucent wall and having means extending outwardly of the wall for supporting said lamp support and forming a guide adapted to receive said spike and resiliently engage said spike for frictionally holding said translucent wall and lamp support in adjusted position on said spike.

2. In a lighting fixture for a garden, in combination, a translucent wall; a spike adapted to extend into the ground and supporting said wall; a lamp support; and means for supporting said lamp support, said means having a portion stationarily embedded in said translucent wall and having guide portions outside said wall below and above said embedded portion, said guide portions being adapted to receive said spike, one of said guide portions being adapted to resiliently engage said spike for frictionally holding said translucent wall and lamp support in adjusted position on said spike.

3. In a lighting fixture for a garden, in combination, a translucent wall; a spike adapted to extend into the ground and supporting said wall; a lamp support; a member forming guide means for the spike and adapted to carry said lamp support, a portion of said member being embedded in the wall; and a spring carried by the guide means and frictionally bearing against said spike.

4. In a lighting fixture for a garden, in combination, a

translucent wall; a spike adapted to extend into the ground and supporting said wall; a lamp support; a member forming guide means for the spike and adapted to carry said lamp support, an integral portion of said member being embedded in the wall; and a leaf spring interposed between the guide means and spike for frictionally retaining the wall in position relative to the spike.

5. In a lighting fixture for a garden, in combination, a translucent wall; means for supporting the wall above ground; means forming a lamp support, said last means having a portion embedded in the wall and having a portion forming a reflector for a lamp carried by the support, said latter portion being spaced from the wall to provide heat-insulating space between it and said latter portion.

6. In a lighting fixture for a garden, in combination, a translucent wall; means for supporting the wall above ground; means forming a lamp support, said last means having a portion embedded in the wall and having an integral portion forming a reflector for a lamp carried by the support, said latter portion being spaced from the wall to provide heat-insulating space between it and said latter portion, said last means including a portion extending transversely of the other two portions and interconnecting the same, said interconnecting portion forming a guide for a spike.

7. In a lighting fixture for a garden, in combination, a translucent wall; means for supporting the wall above ground; means forming a lamp support, said last means having a portion embedded in the wall and having a portion forming a reflector for a lamp carried by the support, said latter portion being spaced from the wall to provide heat-insulating space between it and said latter portion, said last means including a portion extending transversely of the other two portions and interconnecting the same, said interconnecting portion forming a guide for a spike, said last means also including a portion spaced from said interconnecting portion, said last-mentioned portion and said interconnecting portion having aligned openings for receiving a spike.

8. In a lighting fixture for a garden, in combination, a translucent wall; a spike adapted to extend into the ground and supporting said wall; a lamp support; a member forming guide means for the spike and adapted to carry said lamp support, a portion of said member being embedded in the wall and a portion of said member forming a reflector for a lamp carried by the support, said latter portion being spaced from the wall to provide heat-insulating space between it and the wall.

9. In a lighting fixture for a garden, in combination, a translucent wall; a spike adapted to extend into the ground and supporting said wall; a lamp support; a member forming spaced guide means for the spike and adapted to carry said lamp support, said member having an intermediate portion embedded in the wall, said member including a portion connected with one of the guide means and extending substantially parallel with the wall, said latter portion being spaced from the wall to provide heat-insulating space between it and the wall.

10. In a lighting fixture for a garden, in combination, a translucent wall; a spike adapted to extend into the ground and supporting said wall; a lamp support; a member forming spaced guide means for the spike and adapted to carry said lamp support, said member having an intermediate portion embedded in the wall, said member including a portion connected with one of the guide

means and extending substantially parallel with the wall, said latter portion being spaced from the wall to provide heat-insulating space between it and the wall; and a spring carried by the other of said guide means and frictionally bearing against said spike.

11. In a lighting fixture for a garden, in combination, a translucent wall; a spike adapted to extend into the ground and supporting said wall; a lamp support; a member having a portion embedded in the wall and having portions extending outwardly from the ends of the embedded portion and outwardly of the wall, said outwardly extending portions providing aligned guide means for the spike, said member including a portion connected with one of the outwardly extending portions and lying substantially parallel with the wall, said latter portion being spaced from the wall to provide heat-insulating space between it and the wall; and a leaf spring interposed between the other of said guide means and the spike for frictionally retaining the wall in position relative to the spike.

12. In a lighting fixture for a garden, in combination, a translucent wall; a spike adapted to extend into the ground and supporting said wall; a lamp support; a member carrying the lamp support, said member having portions embedded in the wall and having portions extending outwardly from confronting ends of the embedded portions and outwardly of the wall, said outwardly extending portions providing guide means for the spike; and a leaf spring interposed between the guide means and spike for frictionally retaining the wall in position relative to the spike, said member including another portion extending outwardly from another end of one of the embedded portions and extending outwardly of the wall, said last-mentioned outwardly extending portion forming a guide means for the spike, said last-mentioned guide means being aligned with the other two guide means.

13. In a lighting fixture for a garden, in combination, a translucent wall; a spike adapted to extend into the ground and supporting said wall; a lamp support; a member carrying the lamp support, said member having portions embedded in the wall and having portions extending outwardly from confronting ends of the embedded portions and outwardly of the wall, said outwardly extending portions providing guide means for the spike; and a leaf spring interposed between the guide means and spike for frictionally retaining the wall in position relative to the spike, said member including another portion extending outwardly from another end of one of the embedded portions and extending outwardly of the wall, said last-mentioned outwardly extending portion forming a guide means for the spike, said last-mentioned guide means being aligned with the other two guide means, said member including a portion connected with said last-mentioned guide means and extending substantially parallel with the wall, said latter portion being spaced from the wall to provide heat-insulating space between it and the wall.
